UNITED STATES PATENT OFFICE.

JAMES W. WRIGHT, OF LOS ANGELES, CALIFORNIA.

THERMALLY-INSULATED PICNIC BOX.

Application filed October 12, 1922. Serial No. 593,971.

To all whom it may concern:

Be it known that I, JAMES W. WRIGHT, a citizen of the United States, residing at Los Angeles, in the county of Los Angeles and 5 State of California, have invented new and useful Improvements in Thermally-Insulated Picnic Boxes, of which the following is a specification.

This invention relates to receptacles and 10 more particularly to thermally insulated boxes.

It is an object of the present invention to provide an extremely simple and inexpensive form of thermally insulated receptacle 15 and more particularly a thermally insulated box adapted for picnic uses and capable of being readily carried about by hand.

It is another object of the invention to provide a thermally insulated box of hollow 20 wall construction and which is reinforced so as to be capable of standing considerable external pressure when the wall is vacuumized.

Other objects and advantages will be made 25 manifest in the following specification of an embodiment of the invention illustrated in the accompanying drawings, wherein:

Figure 1 is a vertical section of the device 30 showing the top in closed position.

Figure 2 is a perspective of the device showing the top closed and fastened.

Figure 3 is a perspective of the box showing the top removed.

The present thermally insulated box consists of side walls and a bottom all rigidly fastened, the walls having inner panels 2 and an inner bottom 3 which may be of tin or other durable material and the panels and bottom are spaced from an intermediate tin 35 wall 4 by spacing means consisting of blocks of cork 5, each supported within a jacket of non-heat conducting property, such, for instance, as fiber tubes 6'.

The reinforcing cork blocks 5 are sufficiently closely spaced to form a substantial support for the intermediate wall 4 and the intermediate bottom 5'. The intermediate walls and intermediate bottom are surrounded closely by an insulating partition 6, such as of asbestos, and this insulating covering is in turn enclosed in a protecting outer shell 7. The top of the box is open and has a downwardly and inwardly beveled cork or other seal forming seat 8 upon 50 which may be snugly disposed a cover 10 which is of hollow construction obtained in

the manner above described with respect to the walls of the box.

The hollow walls and bottom all form a communicating vacuum space and one of 60 the walls is provided with a valve or air exhausting block 11 having an exhaust port 12 opening into the vacuum space in the walls. The port 12 is designed to be closed off by a valve screw 13 which is run in after 65 a suitable degree of vacuum has been obtained in the vacuum space.

The top 10 is provided with a vacuum block or valve device 11 of the kind above described.

In Fig. 1 the suction hose H of a vacuum pump is shown as attached to the vacuum block 11 indicating the manner of exhausting the air from the vacuum space in the top. After the air has been exhausted the valve 75 screw 13 is then closed and the hose H removed.

Suitable means are provided for securing the top 10 in closing position and such means is also utilized as a handle for carrying the box. Such fastening and carrying means is shown as including a handle or bail 15 having bent side arms 16 connected to a rock shaft 17 journaled in a suitable bearing 18 fastened to a side of the box. A pair of 80 the bails of this top being attached to diametrically opposite sides of the box, may be turned from the open position of Figure 3 to the closing position of Figure 2 to bring the handle parts 15 of the bails together and these may then be hooked or clamped in fastening position by hooks 19 turnably mounted on the side arms of the bail so as 85 to lock these arms together.

From the above it will be seen that I have 90 provided an extremely simple and practicable form of thermally insulated box of inexpensive but substantial and effective construction.

It is understood that the reinforcing 100 blocks or spacers 5 may be of cork or other suitable material having non-heat conductive property, and preferably these blocks are of vegetable matter.

The intermediate asbestos layer 6 between 105 the metallic walls forms not only a heat insulator, but also a friction spacer or filler between the contiguous metallic plates.

Further embodiments, modifications and variations may be resorted to within the 110 spirit of the invention as here claimed.

What is claimed is:

1. A thermally insulated picnic box comprising inner side walls and a bottom wall all rigidly connected, intermediate side walls and a bottom wall all rigidly connected and spaced from the inner walls and bottom, blocks of cork having jackets of non-heat conducting material mounted in the space between the inner and intermediate constructions and evenly distributed to form braces, an insulating partition outside of the intermediate walls and bottom and a protecting outer shell covering the insulation, the container thus constructed being open at the top and having a pocketed beveled edge all the way around, cork in the pocket forming a seat, a cover adapted to fit the seat, said cover being constructed in the same manner as one of the sides or bottom and the air being exhausted from the spaces between the inner walls and the intermediate walls, and bails connected to the sides of the box and adapted to be folded up over the cover and fastened in closed position to form handles and to lock the top in closed position. 45
2. A thermally insulated picnic box comprising inner side walls and a bottom wall rigidly connected, intermediate side walls and a bottom wall all rigidly connected and spaced from the inner walls and bottom, blocks of cork having jackets of non-heat conducting material mounted in the space between the inner and intermediate constructions and evenly distributed to form braces, an insulating partition outside of the intermediate walls and bottom and a protecting outer shell covering the insulation, the container thus constructed being open at the top and having a pocketed beveled edge all the way around, cork in the pocket forming a seat, and a cover adapted to fit the seat. 50
3. A thermally insulated picnic box comprising inner side walls and a bottom wall rigidly connected, intermediate side walls and a bottom wall all rigidly connected and spaced from the inner walls and bottom, blocks of cork having jackets of non-heat conducting material mounted in the space between the inner and intermediate constructions and evenly distributed to form braces, an insulating partition outside of the intermediate walls and bottom and a protecting outer shell covering the insulation, the container thus constructed being open at the top and having a pocketed beveled edge all the way around, cork in the pocket forming a seat, a cover adapted to fit the seat, said cover being constructed in the same manner as one of the sides or bottom and the air being exhausted from the spaces between the inner walls and the intermediate walls. 55
4. A thermally insulated picnic box comprising inner side walls and a bottom wall rigidly connected, intermediate side walls and a bottom wall all rigidly connected and spaced from the inner walls and bottom, blocks of non-heat conducting material mounted in the space between the inner and intermediate constructions and evenly distributed to form braces, an insulating partition outside of the intermediate walls and bottom and a protecting outer shell covering the insulation, the air being exhausted from the spaces between the inner walls and the intermediate walls, and the container thus constructed being open at the top and having a pocketed beveled edge all the way around, means in the pocket forming a seat, and a cover adapted to fit the seat, said cover being constructed in the same manner as one of the sides or bottom. 60
5. A thermally insulated picnic box comprising inner side walls and a bottom wall all rigidly connected, intermediate side walls and a bottom wall all rigidly connected and spaced from the inner walls and bottom, blocks of cork having jackets of non-heat conducting material mounted in the space between the inner and intermediate constructions and evenly distributed to form braces, an insulating partition outside of the intermediate walls and bottom and a protecting outer shell covering the insulation, the container thus constructed being open at the top and having a pocketed beveled edge all the way around, cork in the pocket forming a seat, a cover adapted to fit the seat, said cover being constructed in the same manner as one of the sides or bottom. 65
6. A thermally insulated picnic box comprising inner side walls and a bottom wall rigidly connected, intermediate side walls and a bottom wall all rigidly connected and spaced from the inner walls and bottom, blocks of non-heat conducting material mounted in the space between the inner and intermediate constructions and evenly distributed to form braces, an insulating partition outside of the intermediate walls and bottom and a protecting outer shell covering the insulation, the air being exhausted from the spaces between the inner walls and the intermediate walls, and the container thus constructed being open at the top and having a pocketed beveled edge all the way around, means in the pocket forming a seat, and a cover adapted to fit the seat, said cover being constructed in the same manner as one of the sides or bottom. 70
7. A thermally insulated picnic box comprising inner side walls and a bottom wall rigidly connected, intermediate side walls and a bottom wall all rigidly connected and spaced from the inner walls and bottom, blocks of non-heat conducting material mounted in the space between the inner and intermediate constructions and evenly distributed to form braces, an insulating partition outside of the intermediate walls and bottom and a protecting outer shell covering the insulation, the air being exhausted from the spaces between the inner walls and the intermediate walls, and the container thus constructed being open at the top and having a pocketed beveled edge all the way around, means in the pocket forming a seat, and a cover adapted to fit the seat, said cover being constructed in the same manner as one of the sides or bottom. 75
8. A thermally insulated picnic box comprising inner side walls and a bottom wall rigidly connected, intermediate side walls and a bottom wall all rigidly connected and spaced from the inner walls and bottom, blocks of non-heat conducting material mounted in the space between the inner and intermediate constructions and evenly distributed to form braces, an insulating partition outside of the intermediate walls and bottom and a protecting outer shell covering the insulation, the air being exhausted from the spaces between the inner walls and the intermediate walls, and the container thus constructed being open at the top and having a pocketed beveled edge all the way around, means in the pocket forming a seat, and a cover adapted to fit the seat, said cover being constructed in the same manner as one of the sides or bottom. 80

In testimony whereof I have signed my name to this specification.

J. W. WRIGHT.
